[57]

ABSTRACT

A surface-mounted door holder-closer responsive to the particulate products of combustion passing through multiple passageways formed in a holder-closer housing cover, a holder-closer assembly frame, and a dark chamber which is an integral part of a photocell particle detector module. The particle detector module is insertable into the holder-closer frame with the frame and dark chamber walls not only defining the passageways, but also isolating the chamber from spurious light entering the chamber which would render a false alarm or false emergency door release. The frame also houses the principal components of the holder-closer, namely, a closer spring, a dashpot, a latching lever assembly, and an electromagnet responsive to modulated output current flow from the dark chamber to effect alarm or emergency release of the latching lever to close an otherwise open door. The integrated detector-holder-closer is advantageously and simply mounted on the lintel or header of a door frame.

Jan. 7, 1972, now U.S. Pat. No. 3,777,423 for Condition Responsive Door Holder-Closer.

BACKGROUND OF THE INVENTION

The prior art is prolific in door holder-closer structures responsive to the products of combustion to effect an alarm or emergency release of open doors. Where such doors are released by detectors, several approaches have been employed, generally ranging from door release by a complex central fire alarm system characterized by detectors spaced throughout a structure under surveillance to a simple form of a fusible element mounted on the arm of a door closer.

The most common type of quick response detector employed has been a photocell (refraction type) detector or an ionization detector mounted on the ceiling of a corridor, approximately five feet from a fire resistant door to effect a barrier which will prevent passage of the products of combustion from one section of a building to another. As a general rule, if the top of the door, or lintel, extends below the corridor ceiling over eighteen inches, it is standard practice to install a second detector on the opposite side of the door, again approximately five feet from the door. The corridor closure may be a single door or a dual door using an electromagnetic door holder-closer on each door. In any event, each detector is located remotely from the controlled holder-closer. Accordingly, at least two units must be separately mounted with interconnecting wiring.

In the event products of combustion are generated, a detector located on the ceiling causes the release of all controlled doors to close the corridors. At this stage, personnel evacuation of a building is possible since the doors will open in the direction of egress from the building. However, in many cases premature and unsafe door closing is effected because the detection of ceiling smoke will occur well before the exitways

SUMMARY OF THE INVENTION

30 The invention herein described incorporates a photocell particle detector module in the holder-closer housing. The housing is preferably located above the door on the lintel or header of the door frame. Any products of combustion pass through multiple passageways located within the holder-closer housing to actuate the detector. Location of the detector at this point and within the holder-closer housing effects a major safety advantage. Instead of each controlled door closing at the first evidence of smoke at the ceiling (and the ceiling 35 may be from seven to fourteen feet high), each door will now remain open until the smoke "level" builds downwardly from the ceiling to the height of the door — leaving the doors open for persons to move in either direction — until such time as smoke or products of combustion begin to block the actual exitway.

It is impossible to predict the logic of most persons under a fire or panic condition. Faced with closed doors, many persons will panic even though the doors will manually open with a normal force. Moreover, 50 early door closing is highly disadvantageous for those buildings within which non-ambulatory patients are housed.

55 The location of the detector near the center of the door or, in the case of a double door closure, near the center of the corridor, is simply the best location to detect smoke or products of combustion. This detector location is effectively attained by this invention because the end of the closer-holder housing containing the detector is generally so located. There is a natural flow of air or draft through a closure opening. This flow will carry the products of combustion through this opening and also effectively through the detector fluid flow passageways formed into the surface mounted holder-closer of this invention. The detector, however, 60 is not actuated until the exitway is subject to smoke passage; thus, facilitating evacuation until the last possible safe moment.

Additionally, the present invention has the economic advantage that regardless of the height of the corridor ceiling relative to the height of the door, one detector is all that is required to properly monitor the door. The interconnection of separated detectors and controlled holder-closers is eliminated.

DETAILED DESCRIPTION OF THE DRAWINGS

In order that all of the structural features for attaining the objects of this invention may be readily understood, reference is herein made to the drawings, wherein:

FIG. 1 is a view showing the surface application of the condition responsive door holder-closer of this invention to a single door;

FIG. 2 is a view showing the application of one door holder-closer of this invention to control a pair of corridor doors;

FIG. 3 is an exploded view showing certain principal components of the door holder-closer, namely, the photocell particle detector module, the holder-closer assembly, and the cover;

FIG. 4 is an exploded fragmentary view showing the top-bottom access openings for the products of combustion in the cover, the photocell particle detector module, and the holder-closer frame;

FIG. 5 is a section view taken along line 5—5 of FIG. 4 showing the relative alignment of the front-top-bottom openings of the cover, frame and module which provide fluid flow access to the photocell dark chamber;

FIG. 6 is a top view with certain components being broken away to show the top and bottom circularly disposed access openings;

FIG. 7 is a partial front view of that portion of the cover having the combustion products access openings;

FIG. 8 is a perspective view of the particle detector with a portion of the chamber wall being broken away to expose the internal disposition of the components within the chamber;

FIG. 9 is a bottom fragmentary view of the portion of the door holder-closer containing the photocell particle detector module with certain components being broken away to expose elements of the module chamber and also to show the relative disposition of the module relative the closer spring;

FIG. 10 is a top fragmentary view of the door holder-closer assembly, showing in full or in section the principal components of the holder-closer, namely, the closer spring, dashpot, electromagnet and the latching lever assembly;

FIG. 11 is a front view of the structure of FIG. 10 with the dashpot partially in section (see lines 11—11 of FIG. 10) to show the details of the dashpot and the dashpot rollers;

FIG. 12 is a fragmentary view of the door holder-closer showing the latching lever assembly being manually overridden from a hold-open position and with the electromagnet energized;

FIG. 13 is a fragmentary view of the door holder-closer showing the latching lever assembly being released in response to the deenergization of the electromagnet;

FIG. 14 is a rear view showing the latching lever assembly coupled to the holder-closer dashpot by a fulcrum pin;

FIG. 15 is a section view of the latching lever assembly taken along line 15—15 of FIG. 14;

FIG. 16 is a schematic circuit, with the principal components of the door holder-closer being diagrammatically shown, which shows the failsafe connection of the photocell particle detector module to its associated circuitry;

FIG. 17 is a view showing the surface application of a second embodiment of the condition responsive door holder-closer of this invention to a door;

FIG. 18 is a view similar to that of FIG. 9 showing, however, a second form of photocell particle detector;

FIG. 19 is a section view taken along line 19—19 of FIG. 18;

FIG. 20 is a detailed view showing the two source light paths taken in the photocell particle detector of FIGS. 18 and 19; and

FIG. 21 is a schematic circuit showing the connection of the particle detector of the second embodiment to the schematic circuitry of FIG. 16.

DETAILED DESCRIPTION OF THE PREFERRED EMBODIMENT

Referring now to FIG. 1, the condition responsive electromechanical door holder-closer 1 of this invention is shown typically applied to a flush door 2 which is supported by a plurality of butt hinges 3 (only one of which is shown) upon a conventional metal door frame 4.

In general, door holder-closer 1 includes a track 5 within which a slide block (not shown) reciprocates. The left end of standard arm 6 is coupled to the slide block. The right end of arm 6 is coupled to the projecting end of a rotating drive spindle (114 of FIG. 11) which is an integral part of the holder-closer dashpot.

The door holder-closer housing includes a cover 7 which contains the principal components of this invention, namely, a photocell particle detector module, a coil spring, a link chain, a dashpot and an electromagnetic lever assembly.

In the usual preferred installation of door holder-closer 1, cover 7 and its contained components are fixedly positioned on the header trim 8 of door frame 4, and track 5 is fixedly positioned immediately below cover 7 adjacent the upper edge of flush door 2 as is shown in FIG. 1.

As is shown in FIGS. 1, 3, 4 and 5, cover 7 has a planar bottom wall 9, a planar front wall 10 with curved ends, and a planar top wall 11.

Bottom wall 9 is formed with a plurality of circularly disposed openings 12, front wall 10 is formed with two rows of rectangular openings 13, and top wall 11 (FIG. 6) is formed with a plurality of circularly disposed openings 14. As is hereafter outlined in detail, openings 12, 13 and 14 located in cover 7 are so aligned with other openings to provide fluid flow access for the products of combustion to a photocell particle detector which is part of the detector module located within the housing.

FIG. 2 shows the application of one condition responsive door holder-closer 1 of this invention to control a pair of corridor doors 2 and 2'. Each door 2, 2' is controlled by a closer 1, 1', respectively.

It should be noted, however, that only door 2 is controlled by a holder-closer 1 which includes a cover 7 formed with a plurality of openings such as shown with respect to cover 7 of FIG. 1. Holder-closer 1' which

controls door 2' is contained within a cover 7' which has no openings that correspond to openings 12, 13 and 14 of cover 7. In general, holder-closer 1' is constructed in a manner identical to that of condition responsive holder-closer 1 with the exception that no particle detector module is included within the closer 1'. As will be hereinafter outlined, the electrical circuitry of closers 1 and 1' are interconnected so that if holder-closer 1 detects products of combustion, both closers are activated simultaneously so as to close doors 2, 2' in response to such detection. It has been found that it is unnecessary in the application of a pair of doors which close off a hall or corridor to employ individual detectors within each of closers 1 and 1' inasmuch as the single detector is capable of adequate response to close off both doors.

FIG. 3 is an exploded view showing the two principal components of the door holder-closer 1, namely, the particle detector module 15 and the door holder-closer assembly 16. Module 15 is insertable within assembly 16 by module movement in the direction of the arrow, and the combined module holder-closer assembly is enclosed by cover 7 by relative movement of combined components 15 and 16 in the direction of the arrows toward cover 7.

Door holder-closer assembly 16 includes a metallic frame 17 which is generally U-shaped in cross section, having an elongated irregular bottom 18, a connecting back 19, and an elongated irregular top 20. As is shown in FIGS. 3, 4, 5 and 6, frame bottom 18 and frame top 20 are formed with circular openings 21 and 22, respectively. The plurality of cover bottom openings 12 are aligned with frame opening 21 as is shown in FIGS. 3, 4 and 5, so that opening 21 provides bottom access for openings 12 into the interior of frame 17. Similarly, the plurality of cover top openings 14 are aligned with frame opening 22 so that top access may be had into the interior of frame 17 (FIGS. 5 and 6).

In view of the fact that frame 17 has no front covering adjacent frame openings 21 and 22, cover openings 13 permit direct fluid flow access into frame 17 (see FIGS. 3, 5 and 7).

As is shown in FIGS. 3 and 4, particle detector module 15 is an integral electrical unit having a body portion 15a from which a finger portion 15b projects. As is shown in FIGS. 3 and 9, frame 17 is formed with a chamber which will receive module 15. Module 15 comprises a supporting frame having two metallic sides 23 and 24 (FIGS. 3, 5 and 9) joined by a metallic bottom 25. Metallic sides 23 and 24 are fixed in the parallel disposition by means of metallic spacer posts 26 and 27 (FIG. 9).

Electrical components and interconnecting wiring generally denominated by numeral 28 are mounted upon circuit board 29. These components constitute part of the particle detector amplifier hereinafter described. Circuit board 29 is electrically isolated from module bottom 25 by insulating sheet 30.

Referring to FIGS. 5, 8, 9 and 16, a photocell particle detector 31 comprises generally a housing having a light source 33 disposed outside the housing, and a photocell detector element 34 also disposed outside the housing.

Detector 31 is particularly adapted for use as the detector unit of a smoke alarm and for this purpose the housing comprises a peripheral wall or main body portion 35 and a pair of end caps 37 and 38 defining an in-

ternal chamber 36. The end caps extend beyond the periphery of wall 35 and have inwardly turned flanges 39 and 40 which are spaced outwardly from the wall. Each end of wall 35 is provided with a series of outwardly inclined spacing lugs 41, which are adapted to engage frictionally the inner surface of the flanges to retain the caps in assembly. The flanges 39 and 40, in conjunction with the spacing lugs 41, form a peripheral passageway having sets of apertures 49 opening the chamber 36 at each end of the wall to permit smoke to enter the chamber from the surrounding atmosphere. Circular screen segments 50 and 51 cover each of the apertures to prevent particulate matter of a non-combustion variety from entering the chamber.

15 A focusing tube 42 extends through housing wall 35, and a light trap tube 43 is disposed in the housing wall on the opposite side in alignment with the focusing tube 42. These elements direct and control the light beam from source 33. A lens 44 of the converging type is disposed within focusing tube 32, with a focal length such that light from the source 33 is focused in a converging beam onto the bottom of the light trap tube 43, so that the beam from the light has a minimum size at the bottom of said trap, and substantially none of the light 20 from the source falls on any other portion of the interior surface of the housing.

A detector tube 45 extends through the housing wall between the light trap tube and the focusing tube, and is disposed generally perpendicular to the axes thereof.

25 30 A photocell detector element 34 is disposed in the detector tube, and to restrict the field of view of the detector, a lens 46 of the converging type is disposed in the detector tube between the detector element and the chamber. Lens 46 has a focal length such that the image of the detector element is focused onto a minimum area on the opposite surface of the housing wall. The cone of focus of the detector element is directed across the cone of focus of the light beam, so that the detector element views only the medial portion of the 35 light beam and the field of view of the cell at the opposite wall portion is confined to the medial portion of the wall. The photocell does not view the peripheral apertures at the top and bottom of the wall. Hence substantially no light reaches the detector element except light

40 45 appearing in the focus cone of the lens 46. To further insure that a minimum amount of the internal stray light reaches the detector element, the end 47 of the detector tube on the side adjacent the light tube extends forwardly to the cone of focus of the light beam to provide a shield against stray light from the inside surface of the focus tube. The end of the detector tube from this foremost point is inclined rearwardly at an angle such that the inside surface of the detector tube cannot view the inside surface of the focus tube. To prevent stray reflected light from the inside of the light trap tube from reaching the detector lens 46, the side 50 of the end of the detector tube adjacent the light trap tube is provided with an inclined shield 48.

55 The detector element 34 may be any type of device which is responsive to a change in light intensity, such as a photoelectric or a photo-resistive cell. One type of cell which has been found satisfactory is cadmium sulfide, which responds to an increase in light intensity by a decrease in resistance. Hence in the illustrated embodiment a detector circuit hereafter described may be connected to the detector element and adjusted under normal conditions of no smoke so that a predetermined

further decrease in cell resistance will actuate an external alarm connected to the detector circuit. When smoke enters the housing and appears in the light beam, light from the smoke particles in the portion of the light beam viewed by the detector is reflected or diffused onto the detector cell, thereby lowering the resistance of the cell and actuating the alarm circuit.

U.S. Pat. No. 3,382,762 issued May 14, 1968 describes further details of the photocell particle detector.

As is shown in FIGS. 5 and 9, particle detector 31 is supported within module 15 by a plurality of support brackets 53. The detector is also tightly sandwiched between module sides 23 and 24 by a pair of spaced insulating discs 54 and 55 (FIG. 5). Module wall 23 is formed with a plurality of circularly disposed openings 56 (FIG. 4) to permit fluid flow access to the adjacent chamber apertures 49. Similarly, module wall 24 is formed with a plurality of circularly disposed openings 57 (FIG. 5) to permit access to the adjacent chamber apertures 49. Accordingly, fluid flow access into interior chamber 36 is provided by the following three passageways:

1. front passageway — through cover openings 13 to the adjacent chamber apertures 49 (FIGS. 3, 5, 7 and 8);
2. bottom passageway — through cover openings 12, frame opening 21, circularly disposed module wall openings 56 to the adjacent chamber apertures 49 (FIGS. 3, 4 and 5); and
3. top passageway — through cover openings 14, frame opening 22, circularly disposed module wall openings 57 to the adjacent chamber apertures 49 (FIGS. 5 and 6).

As is hereinafter outlined with reference to the schematic-diagrammatic representation of FIG. 16, fluid flow, i.e. the passing of the particulate products of combustion through the foregoing passageways affects the electrical resistivity or other characteristics of photocell 34 so that appropriate amplifier circuitry can detect such products.

The principal components of door holder-closer 1 which cooperate with particle detector module 15 will now be described. Referring to FIGS. 10 and 11, support frame 17, which is enclosed within cover 7, houses the following principal components; namely, spring coil assembly 79, link chain 80, dashpot 81, electromagnet 82 and latching lever assembly 83.

Latching lever assembly 83 is described in U.S. Pat. No. 3,729,771, issued May 1, 1973 to Burke J. Crane et al for Latching Lever Assembly for Door Holder-Closer.

Spring assembly 79 includes compression coil spring 84 which envelops a spring rod 85. The left end of spring rod 85 is threaded (FIGS. 9 and 10) so that the adjacent end of spring 84 is held by spring retainer 86. Retainer 86 is adjustably mounted relative threaded rod 85 by washer 87 and spring tension adjusting nut 88.

The right end of spring 84 is supported on spring support plate 89 which has a retaining circular flange 90. Flange 90 receives the adjacent contacting spring 84 turn. Accordingly, spring 84 is positioned relative to rod 85 by spring retainer 86 and spring support plate

89 so that adjustment of nut 88 can vary the static compression force generated by spring 84.

Lateral movements of spring 84 relative to frame 17 are limited by front spring guide 91 and rear spring guide 92.

The right end of spring rod 85 (FIGS. 10 and 11) is coupled to link chain 80 by connecting pin 93. The right end of link chain 80 is coupled to dashpot 81 by connecting pin 94.

10 The details of the dashpot, particularly with reference to FIGS. 10 and 11, will now be described. In FIG. 10, a simplified horizontal section view of the dashpot is shown and in FIG. 11 a simplified vertical section view taken along lines 11—11 of FIG. 10 is shown.

15 In its principal aspects, dashpot 81 comprises a fixed stator 95 which is housed within cavity 96 defined by generally cylindrical rotor 97. Stator 95 is formed with a pair of stator vanes 98 and 99. The stator and its vanes remain fixed at all times relative support frame 17. Stator 95 is formed with a mounting flange 100 (FIG. 11) which is fixed to frame top 20 by a plurality of screws 101.

20 Rotor 97 supports a pair of integral vanes 102 and 103 (FIG. 10) which rotate with the rotor. As is shown in FIG. 11, rotor 97 comprises a cylindrical section 104 to which annular flanges 105 and 106 are fixedly attached. The rotation of rotor 97 produces a corresponding rotation of annular flanges 105 and 106.

25 Connecting pin 94 extends between flanges 105 and 106 to anchor chain 80 responsively to rotor 97. Likewise, roller pins 107 and 108 extend between the flanges so that rollers 109 and 110 may rotate relative their associated pins and between the flanges. Rollers 109, 110 also move responsively with rotor 97 and flanges 105, 106.

30 The interior dashpot cavity 96 defined between rotor 97 and stator 95 contains a viscoelastic plastic solid. This material may preferably be either a natural or synthetic unvulcanized rubber or an elastomeric-like material known as "bouncing putty". This damping medium is contained with cavity 96 by means of O-ring seal 111; damping adjusting screw 112 is manually movable within its threaded bore to exert a varying pressure upon the damping medium through port 113 (FIG. 11). Rotor spindle stem 114 receives the lower end of rotor cylindrical section 104 so that elements 104, 114 rotate in unison. Consequently, the attachment of standard arm 6 to spindle stem 114 produces related movement between arm 6 and the dashpot rotor elements. Rotor elements 104, 114, including flanges 105 and 106 are rotatably fixed relative frame 17 by bearing plates 115 and 116.

35 Stepped pin 117 serves as an alignment bearing for rotor 97 relative stator 95.

40 As is shown in FIG. 10, electromagnet 82 and lever assembly 83 are closely associated with dashpot 81. In particular, electromagnet 82 is supported on frame 17 by electromagnet support plate 117.

45 Referring now principally to FIGS. 10, 11, 13, 14 and 15, the latching lever assembly 83 will now be described. The principal elements of lever assembly 83 are lever 120, lever fulcrum shaft 121, lever assembly biasing spring 122, armature-lever coupling spring 123, armature plate 124, screw-washer-nut 125, and spring alignment cylinder 126.

50 Lever 120 is formed with a latch detent 127 whose main function is to engage rollers 109 and 110 to effect

hold open. The lever is also formed with a yoke having legs 128 and 129 from which lugs 131 and 132 project to receive coupling spring 123.

Coupling spring 123 (FIG. 14) is a helical wound torsion spring formed into two divided and joined sections 133 and 134 having a central spring connector loop 135 (FIG. 15) and two end connector loops 136 and 137 (FIG. 14).

Spring 123 is shown in its tensioned position; that is, end connector loops 136 and 137 have been relatively rotated under spring tension so that loops 136 and 137 are adjacent central connector loop 135 as is shown in FIG. 15. This disposition of connector loops 135, 136 and 137 places spring sections 133 and 134 in torsional tension. Accordingly, when loop 135 is rigidly fixed to armature 124 by bolt and nut 125 (FIG. 15) and end connector loop 136 is fixed to lug 131 and end connector loop 137 is fixed to lug 132 (FIG. 14), coupling spring 123 develops a strong torsional force which tends to force armature plate 124 against lever 120 as is shown in FIGS. 10, 13 and 15. However, it should be noted that as shown in FIG. 13, the resiliency of spring 123 enables armature plate 124 to be separated from lever 120 in response to oppositely directed forces as will be hereafter outlined.

When door 2 is closed, as is shown in FIG. 1, and regardless of the energized or deenergized condition of electromagnet 82, lever assembly 83 assumes the position shown in FIG. 10. As is shown in this Figure and also FIG. 14, lever 120 is pivoted relative dashpot 81 by fulcrum pin 121. Fulcrum pin 121 also receives biasing spring 122 so that a force is exerted by this spring which normally urges the lever assembly to the position shown in FIG. 10; that is, a position in which armature 124 rests against electromagnet 82.

When electromagnet 82 is energized, armature 124 is magnetically attracted to the core of the electromagnet. However, as door 2 is opened, rotor 97 (FIGS. 12 and 13) is rotated counterclockwise moving therewith by chain 80 and thus compressing closer spring 84. The counterclockwise motion of the rotor also causes rollers 110 and 109, in that sequence, to pass under latching detent 127, thus elevating lever 120 as is shown in FIG. 12. Armature 124, however, is magnetically fixed against electromagnet 82 in response to the energization of this electromagnet.

As the rotor 97 is rotated counterclockwise a further slight angle from that shown in FIG. 12, roller 109 (or roller 110 depending upon the amount of angular hold-open desired) is held in engagement against latching surface 127a of latching detent 127. With this occurrence, lever 120 is lowered so that it assumes the relative position with respect to armature 124 shown in FIG. 10. Door 2 is thus held open by the engagement of either roller 109, 110 and latching surface 127a.

In the event it is decided to manually override the hold-open latch of door holder-closer 1, the clockwise movement of rotor 97 causes rollers 109, 110 to elevate or cam away lever 120 so that the closer spring 84 can rotate rotor 97, thereby causing standard arm 6 to move within track 5 to close door 2.

It is important to note that during this condition of manual override, armature 124 is retained against electromagnet 82 as is shown in FIG. 12. In other words, during manual override, armature 124 always maintains contact with electromagnet 82. The resiliency of coupling spring 123 enables lever 120 to move up-

wardly without a corresponding movement in armature 124.

In the event door 2 is held open in response to the engagement of either roller 109, 110 with respect to 5 latching surface 127a, and electromagnet 82 is deenergized due to the opening of a manual operate switch or the detection of an undesired condition by particle detector 31, lever assembly 83 is released as is shown in FIG. 13 and rollers 109, 110 cam latching detent 127 10 upwardly. In view of the fact that electromagnet 82 is deenergized, a holding force is not applied to armature 124 and the armature maintains its contact position with respect to lever 120 as a result of the torsional forces applied to armature 124 and lever 120 by coupling spring 123.

In all situations in which electromagnet 82 is deenergized, lever latching assembly 83 produces a characteristic release noise which is undesirable. However, in the usual installation of a holder-closer of the type described, an emergency or alarm release rarely occurs; accordingly, such noise can be tolerated. Manual override, however, is a commonplace occurrence, and in this instance latching lever release noises can attain an intolerable frequency unless eliminated by appropriate 20 latching lever designs.

The schematic circuit of FIG. 16 shows an electrical circuit effecting the interconnection of electromagnet 82 to particle detector 31 to effect hold-open and closing of door 2 in a failsafe manner of operation. Additionally, the schematic circuitry incorporates a condition responsive detector and amplifier unit within module 15 which is failsafe in operation. In particular, if all 30 of the components of the module 15 are properly operating, door 2 will remain in hold-open effected by the latching of either roller 109 or 110 against latching detent 127 in response to the manual closing of control switch 151. If, however, module 15 is not properly operating or, alternatively, this unit senses a condition such as flame or smoke, door 2 will be released from 35 a latched hold-open position effected either by roller 109 or 110 and closed in response to the closing force exerted by coil spring 84.

The detailed operation of the circuitry of FIG. 16 is 40 as follows. Assuming module 15 is in proper operating condition and that the particle detector 31 input applied to terminals 152 and 153 indicates an absence of a flame or smoke condition, door 2 will be held in the open position in response to the manual closing of switch 151; that is, the closing of switch 151 applies line voltage from terminals 154 and 155 to amplifier A of module 15. The application of line voltage to amplifier A energizes amplifier output relay 156, thereby closing normally open contact 156a.

The closing of contact 156a applies line voltage to 45 the coil of power relay 157. With this occurrence, normally open contact 157a is closed, thereby applying line voltage to fullwave bridge rectifier 158 to energize electromagnet 82 with a pulsating-direct-current voltage. (The physical position of a module containing 50 bridge 158 is shown in FIGS. 10-13).

The energization of electromagnet 82 causes magnetic armature 124 to resiliently hold lever 120 downwardly (FIG. 10) and into locking engagement with either roller 109 or roller 110 against latching detent 127 (if door is manually opened).

Accordingly, lever 120 holds rotor 97 with sufficient force to overcome the otherwise closing force exerted

by coil spring 84. Thus, so long as the electromagnet 82 is energized, door 2 will be held in an open position.

In the event, however, (a) a slight manual closing force is applied to door 2, (b) switch 151 is opened, (c) module 15 malfunctions, or (d) an undesired condition such as smoke or flame is detected by detector 31, lever detent 127 will be pivoted from engagement with roller 109 or 110, as the case may be, and spring 84 will close the door to the position shown in FIG. 1.

In the situation of case (a) above, the manual override closing force causes disposition of the lever assembly 83 components as shown in FIG. 12 during the point of operation at which roller 109, for example, is in camming engagement with latching detent 127.

In situations (b), (c) and (d) above, electromagnet 82 is deenergized, thereby enabling the camming action of roller 109 or 110, as the case may be (see FIG. 13), to elevate lever 120 as well as armature 124 as is shown in this Figure.

In a multiple door installation, such as the corridor application shown in FIG. 2 in which only holder-closer 1 need incorporate a detector module 15, the electromagnet of holder-closer 1' is merely interconnected with the circuitry for holder-closer 1 so that both electromagnets (corresponding to electromagnet 82) are energized or deenergized simultaneously.

Reset pushbutton switch 62 is connected to amplifier A of module 15 so that the circuitry can be again placed in a detecting readiness condition after the closer has released in response to a fire or alarm condition. Switch 62 is accessible for manual operation from the front of cover 7 (FIGS. 7 and 9).

Pilot light 63 is also connected to amplifier A of module 15. When the circuitry is in a properly operating supervisory condition, the pilot light will periodically emit light. When a fire, etc. is detected, the pilot light will remain on. A deenergized pilot light indicates an electrical malfunction. In a preferred circuit arrangement the circuitry "locks" into an alarm condition (pilot light 63 on) and remains in an alarm condition until the unit is reset by manual operation of switch 62.

FIGS. 17 through 21 show a second embodiment of the invention which in general is characterized by the use of a second form of photocell particle detector 64. Particle detector 31, employed in the first embodiment, is characterized by a detector element 34 which is operated by light diffusion or reflection in response to the entry of products of combustion into internal chamber 36. The particle detector 64 of the second embodiment is characterized by light absorption or attenuation of light traveling from a light source to a photocell detecting element.

Referring to FIGS. 17 and 19, the front of cover 7 is formed with two elongated slots 65, the bottom is formed with a single elongated slot 66, and the top is formed with an identical elongated slot 67. The particular form and disposition of slots 65, 66 and 67 enable efficient passage of the particulate products of combustion into the interior of the door holder-closer 1. More particularly, these products must pass into elongated detector tube 68 so that light emanating from source 33 (FIGS. 18, 20 and 21) may be absorbed or attenuated in its path of travel to photocell 69. Detector tube 68 is formed by a plurality of spaced support plates 70 which extend from the front to the rear of tube 68. The peripheral edges of support plate 70 carry blackened wire screen 71 whose interstices permit the passage of

smoke into the interior chamber of detector tube 68. Each of the plates 70 is formed with a central hole 72. Accordingly, light emanating from source lamp 33 travels through light conduit elbow 73 (FIG. 20) in a path of travel in which the light is reflected from mirror surface 74 through lens 75 through the plurality of axially aligned holes 72 to impinge upon photocell 69.

Light from source 33 also travels through a second path which includes second light conduit elbow 76. Light traveling in this conduit elbow is reflected by mirror 76 and follows a path through lens 77 into closed standard tube 78 to thus impinge upon photocell 160. The interior chamber formed by standard tube 78 is hermetically sealed and, accordingly, any products of combustion cannot enter this tube and, therefore, no light absorption occurs within this tube during smoke entry into the inner confines of closer 1.

Referring now to FIG. 21, photocells 69 and 160 are connected in a bridge circuit with variable resistors 161 and 162. Output terminals 152 and 153 of the bridge circuit correspond to like numbered terminals shown in the schematic circuit of FIG. 16. Likewise, terminals 60 and 61 connected to lamp 33 correspond to the like numbered terminals also shown in FIG. 16. The only circuit change is the substitution of the particle detector 64 for particle detector 31. By making appropriate connections to terminals 60 and 61, 152 and 153, circuit operation is obtained which is substantially identical to that previously described with respect to FIG. 16. Variable resistors 161 and 162 are normally adjusted so that with ambient condition no signal appears at the output of amplifier A. However, in the event smoke enters detector tube 68 through wire screen 71, the bridge becomes unbalanced and a signal change appears at terminals 152 and 153. This signal change is applied to amplifier circuit A in accordance with the operation previously described with reference to FIG. 16, thus causing door holder-closer 1 to close door 2.

It should be understood that the above described embodiments are merely illustrative and that changes can be made without departing from the scope of the invention.

What is claimed is:

1. A condition responsive electromechanical closure holder-closer for use with a closure adapted for relative movement with respect to a closure frame, comprising a housing containing the closure holder-closer and adapted to be surface mounted adjacent and above the closure, a spring located within the housing for exerting a closing force on the closure, a damper located within the housing and coupled to the spring for controlling the spring exerted closing force applied to the closure, an electromagnetic arresting means located within the housing with when energized arrests the spring-damper subcombination from closing an otherwise open closure relative the frame and which when deenergized enables the spring-damper subcombination to close the closure relative the frame, an arm assembly adapted to couple the closure to the closure holder-closer to provide closure control responsive to the energized or deenergized condition of the electromagnetic latch, a photoelectric condition-responsive detector contained within the housing and connected to the electromagnetic arresting means to control the energized or deenergized condition thereof, and means including passageways formed in said housing by which said internally housed detector is subjected to a fluid flow char-

acteristic of the presence of said condition to deenergize an otherwise energized electromagnetic arresting means to thereby enable the holder-closer to release and close an otherwise open closure.

2. A condition responsive door holder-closer comprising a housing, a closer spring and a dashpot disposed within the housing, a drive spindle projecting through the housing and coupled to the spring-dashpot subcombination to be responsive to the damped forces exerted by the subcombination, means within the housing for arresting the spindle at a door holdopen position, means including one or more openings in said housing for defining passageways within said housing to facilitate fluid flow within the housing including the particulate products of combustion, a photocell detector for the particulate products of combustion located within the housing, and means interconnecting the detector to the spindle arresting means to release the spindle in response to the flow of the particulate products of combustion through said housing passageway means.

3. The combination of claim 2 in which the housing is generally horizontally disposed on a door frame immediately over the door, and an arm couples the spindle to the door so that the door and spindle are responsive motionwise to one another.

4. The combination of claim 3 in which the door is pivoted for movement relative the frame, the spindle being located adjacent the pivot axis for the door and generally at one end of the housing, and the passageway defining means being generally located at the opposite end of the housing remote from the pivot axis.

5. The combination of claim 4 in which the door holder-closer housing is elongated and generally horizontally disposed on the surface of the frame.

6. The combination of claim 5 in which the passageway defined through the housing is generally vertical.

7. The combination of claim 6 in which the passageway defined through the housing is both vertical and horizontal attained by openings located on the top, front, and bottom of the housing.

8. A condition responsive door holder-closer contained within a housing, comprising a photocell condition detector located within the housing and responsive to fluid flow carrying the particulate products of combustion, means including one or more openings in said housing defining a fluid flow passageway within said housing to said condition responsive detector, a closer-holder spring-dashpot combination including electrically operated means for arresting the spring-dashpot combination to a door hold-open position with the spring, dashpot and electrically operated means being disposed within the housing, and means interconnecting the condition responsive detector to the electrically operated arresting means whereby the passage of the particulate products of combustion through an opening into the passageway releases an arrested spring-dashpot combination.

9. The combination of claim 8 in which the one or more openings is located generally at one end of the housing, and means located generally at the other end of the housing and projecting therethrough for cou-

pling to a door to effect hold-open and also door release.

10. The combination of claim 9 in which a door opening is defined by a frame having a header portion at the top of the frame, and in which the housing is supported at the top of the frame with the one or more housing openings being generally located toward the mid-portion of the header and the door coupling means being located generally at an end portion of the header.

11. The combination of claim 8 in which a plurality of housing openings defines a complete fluid flow passageway into and out of the housing.

12. The combination of claim 10 in which a plurality of housing openings defines a complete fluid flow passageway into and out of the housing.

13. A condition responsive door holder-closer to control a door pivotally mounted relative an opening defined by a frame having a header portion at the top of the frame, comprising a housing supported above the door on or near the header portion, a closer spring and a dashpot disposed within the housing, a drive spindle projecting through the housing and coupled to the spring-dashpot combination to be responsively rotatable by the damped forces exerted by the combination,

20 the spindle being located adjacent the pivot axis of the door and generally near an end of the housing mounted adjacent an end of the header portion, an arm coupling the projected end of the spindle to the door to also responsively rotate the spindle by forces exerted on the door, a photocell detector for the particulate products of combustion located generally at the opposite end of the housing toward the midportion of the door opening, electrically operated means located within the housing for arresting the spring-dashpot combination to a door hold-open position, and means interconnecting the

25 condition responsive detector to the electrically operated arresting means whereby the passage of products of combustion through the door opening releases an arrested spring-dashpot combination to close an open door.
